UNITED STATES PATENT OFFICE.

THOMAS S. PATTERSON, OF ROSEMONT, PENNSYLVANIA, ASSIGNOR TO THE OIL AND WASTE SAVING MACHINE COMPANY, OF PHILADELPHIA, PENNSYLVANIA, A CORPORATION OF PENNSYLVANIA.

BEARING FOR CENTRIFUGAL SEPARATORS.

No. 74,181.

Specification of Letters Patent.

Patented March 2, 1909.

Application filed February 1, 1907. Serial No. 355,304.

To whom it may concern:

Be it known that I, THOMAS S. PATTERSON, a subject of the King of Great Britain and Ireland, residing at Rosemont, Pennsylvania, have invented certain Improvements in Bearings for Centrifugal Separators, of which the following is a specification.

My invention relates to certain improvements in machines for removing oils, grease, etc., from materials by centrifugal force.

The object of my present invention is to improve the construction of the bearing for the basket of a centrifugal machine and to provide means whereby the lubricant is caused to flow continuously through the bearing while the machine is in operation. This object I attain in the following manner, reference being had to the accompanying drawing, in which:

20 Figure 1, is a vertical sectional view of a centrifugal separator illustrating my invention; Fig. 2, is an enlarged view of the bearing; Fig. 3, is a plan view of the ball cage; Fig. 4, is an edge view of the ball cage shown 25 in Fig. 3.

A indicates the base of the structure supporting the annular shell B which is fastened to the base.

B' is the cover held in place by an arm b having a confining screw b'. The arm is arranged to swing on the standard b² at one side of the machine so that when it is desired to remove the cover the screw b' is backed off, and the arm is turned on its pivot clear 35 of the cover, after which the cover can be removed.

Mounted in the base A is the vertical bearing D having a flange d in the present instance, which is securely fastened to the 40 portion A' of the base forming the bottom of the chamber inclosed by the shell B.

Mounted in the bearing is a vertical spindle C carrying at its upper end the basket E, which has an elongated hub e through 45 which the spindle extends. The spindle is reduced as shown to form a shoulder c' upon which the basket rests, and a nut c confines the basket to the spindle. The hub e and the bottom e' of the basket are preferably formed in one piece, the hub having a cavity e² open at the bottom and the walls of this cavity are perforated so that steam can enter this cavity and pass through the perforations into the interior of the basket. 55 A perforated shell e³ forms the outer wall of

the basket and this shell is supported by heavy steel bands e⁴ in the present instance. Depending from the bottom of the basket is a flange f having wings f' which form the blades of a turbine wheel for driving the 60 basket.

F is the steam pipe having a nozzle f² which is so situated in respect to the said blades f' that when the steam passes from the nozzle it will impinge upon these blades 65 and rapidly rotate the basket. The exhaust steam passes around the outside of the basket and through the passage e² at the center, passing into the basket and through the material contained in the basket. By this 70 means the oil and grease with which the material is saturated or coated is liquefied by the heat and is freed from the material by centrifugal force, passing through the openings in the shell into the outer chamber 75 while the material is held by the shell.

G is the pipe tapped into the bottom plate A' in the form of a trap, and is for the purpose of drawing off the oil or grease as it accumulates in the bottom of the chamber. 80

In this type of machine it is very difficult to properly support the spindle C and to lubricate it, as the tendency is, in all machines driven at a high speed, to throw off the lubricant so that in many cases the bearing 85 becomes heated and is destroyed.

Secured to the bottom of the bearing D is a plate D' and mounted on this plate, as clearly shown in Fig. 2, is a base plate I of a ball bearing. I' is a cap plate and between 90 these two plates I, I' are mounted the balls i held in the cage, consisting of two perforated plates i', i' connected together. It will be noticed that these balls are so situated that each travels in its own concentric path. 95 The plate I' has a central spherical projection i² and the stem C has a cavity c² in its end conforming to the shape of the said projection, although in some instances the projection may be omitted and the stem may rest 100 directly upon the flat portion of the plate I'.

Mounted in the bearing d' is a bushing c³ which supports the central portion of the spindle, the spindle snugly fitting the lower portion d² of the bearing. 105

In order to properly lubricate the bearing I provide a lubricant reservoir M mounted on a bracket at one side of the machine, on a line with the upper portion of the bearing D.

In the plate D' at the base of the bearing is 110

a central opening d^3 and communicating with this opening is a pipe m leading from the bottom of the reservoir M , and in line with the opening d^3 is an opening j^3 in the plate I so that the lubricant will pass into the ball race and from the ball race up through the bearing D to the upper end. Formed in the bearing in the present instance is a channel n which communicates at n' with a pipe m' leading from this point through the bottom of the reservoir M to a point on a line with or slightly below the upper portion of the bearing D . By entering the pipe m at the center of the bearing the centrifugal action will not drive the lubricant away from the bearing but the rotation of the balls and the upper plate, as well as the spindle, will tend to draw the lubricant into the bearing and consequently create a partial vacuum in the reservoir M , this will cause the lubricant when it reaches the enlarged portion d^4 of the bearing to be drawn through the passage n and through the pipe m' to the reservoir, thus circulating the lubricant and keeping the bearing properly lubricated at all times.

While I have shown my invention as particularly applied to a separator in which the basket is driven by a turbine engine, it will be understood that the basket may be driven in any manner desired without departing from the essential feature of the invention.

I claim—

1. The combination in a centrifugal separator, of a vertically arranged bearing, a spindle mounted in the bearing, two plates mounted in the lower portion of the bearing, balls mounted between the plates, the lower plate having a central opening, means for

supplying lubricant through said opening and an outlet for lubricant at the upper end 40 of the vertical bearing.

2. The combination of a vertical bearing, a spindle mounted in the bearing, two plates mounted in the lower portion of the bearing, balls situated between the two plates, said 45 spindle resting upon the upper plate, the lower plate having a central opening, the bearing having a channel in its upper portion, a reservoir at one side of the separator, a pipe leading from the lower portion of the reservoir 50 to the central opening in the bottom plate and another communicating with the above mentioned channel.

3. The combination in a separator of a bearing, a vertical spindle mounted in the 55 bearing, a base plate and cap plate mounted in the lower portion of the bearing, balls mounted between the two plates, the base plate having a central opening and the bottom plate of the bearing also having a 60 central opening, the cap plate having a spherical projection, the spindle having a cavity in its lower end conforming to the said projection on the cap plate, a lubricant reservoir, a pipe leading from the reservoir 65 to the central opening in the bottom of the bearing, and a pipe leading from the upper portion of the bearing to the reservoir.

In testimony whereof, I have signed my name to this specification, in the presence of 70 two subscribing witnesses.

THOMAS S. PATTERSON.
